UNITED STATES PATENT OFFICE.

THOMAS GROSERT AND ERNEST UNGER, OF NEW YORK, N. Y.; SAID GROSERT
ASSIGNOR TO SAID UNGER.

HAIR-STEAMING DEVICE.

1,103,506.

Specification of Letters Patent.

Patented July 14, 1914.

Application filed January 3, 1914. Serial No. 810,136.

To all whom it may concern:

Be it known that we, THOMAS GROSERT and ERNEST UNGER, citizens of the United States, residing in the borough of Manhattan, city, county, and State of New York, have invented certain new and useful Improvements in Hair-Steaming Devices, of which the following is a specification.

Our invention relates to hair steaming and waving devices and constitutes an improvement in devices of the character forming the subject matter of our Patent No. 1,029,361, June 11, 1912.

When the hair has been waved following the process outlined in the above identified patent the waving usually lasts for a period of from six months to one year but during this time the new hair grows out about an inch and as this hair is naturally un-waved it destroys the effectiveness of the waved hair and it has heretofore been necessary to re-wave the entire head of hair at great expense of time and labor.

Accordingly one of the objects of the invention is to provide a heating device of the above indicated character particularly designed to concentrate the heat to the wrapped portions of the hair adjacent the head thereby to wave the hair at this place without affecting the outer portions of the wave coil.

Another object of the invention is to provide a light, compact and balanced hair waving device of simplified construction, the parts of which may be readily assembled as units and effectively secured in place.

Various other objects and advantages will be obvious from an inspection of the illustration of one form of device embodying our invention and in part will be more fully disclosed in the following detailed description thereof.

In the accompanying drawings: Figure 1 is a side elevation of one form of our invention, shown in position on a person's head; Figs. 2 and 4 are enlarged longitudinal sectional views taken axially through the device shown in Fig. 1, and at right angles to each other; Fig. 3 is a transverse sectional view taken on the line 3-3 of Fig. 2 and looking in the direction indicated by the arrow; and Fig. 5 is a rear elevation of the device.

There is shown an inner open ended tube 1 of relatively high heat conductivity made

preferably of brass and when used for the particular purpose for which this device has been designated is of about one inch in length and has a smooth bore of uniform cross-sectional area. Extending outwardly from one end of the tube 1, herein designated as the rear end, is a plate 2 to which is attached a suitable handle 3 preferably covered by suitable insulating material 4. Affixed to the plate 2, and preferably integral therewith, is a projecting lug 5 carrying an insulating bushing 6 to guide the electric conductors 7 therethrough to the heating coil hereinafter described. This lug may also contain an aperture 8 by means of which the device may be suspended in counterweighted position over a suitable pulley as is common with the suspension of devices of this character.

Surrounding the tube 1 and suitably fastened to the plate 2 is an insulating ring 9 preferably of a compressed asbestos composition. The portion of the ring adjacent the bushing 6 has a recess 10 to accommodate the conductor 7, and this ring carries a pair of oppositely disposed binding posts 11, each post having a plurality of nuts 12 threaded thereto. The conductors 7 lead respectively to the binding posts and are held in engagement therewith by the inner nut 12 pressing the same against the adjacent face of the ring 9.

A sleeve 13 of insulating material, preferably mica, surrounds the tube 1 and electrically insulates the same from an electric heating coil 14, the ends of which lead respectively to the binding posts 11 and are held thereto between the nuts 12. The coil 14 is inclosed within an insulating layer 15 and is bound by an asbestos cord 16. In closing this heating device is an outer tubular member 17, preferably of metal, the rear end of which abuts the front face of the ring 9 and the front end of which is frusto-conical as shown at 18. The adjacent front ends of the tubes 1 and 17 are permanently fastened together as by flanging or welding to form in effect a metallic heating ring 18. The heating coil 14 has its front end disposed within the angle formed by these tubular members and as close as possible to the front end or nose of the device. The outer tubular member 17 is preferably inclosed within an insulating outer covering 19.

In operation it will be understood that the hair is coiled and treated as more fully described in the above identified patent and drawn through the tubular member 1 until 5 the pointed front nose is brought flat against or close to the head. The current is then permitted to traverse the heating coil 14 which tends to concentrate the heat as close to the base of the coil of hair as possible 10 as there is no insulating member between the heating device and the inner and outer tubular members and at the same time there is provided sufficient material to give a material heat capacity.

15 This device is of a minimum diameter so that a large number of the devices may be positioned at the same time on the head. The inner member is opened at both ends so that the hair may be drawn therethrough 20 and the part not being waved may be suitably protected from any heating action of the device and is approximately balanced about the rear plate so as to relieve as much strain as possible on the hair.

25 Having thus described our invention, we claim:

1. A device of the class described, comprising an open ended tubular member of relatively high heat conductivity having a cylindrical bore adapted to contain a portion 30 of a coil of hair intermediate its end and permit other portions to extend beyond opposite ends thereof, an outer tubular member having a conical nose affixed thereto at one end 35 and a heating means disposed between said members and filling the space adjacent the connection between the inner and outer tubular members whereby a high degree of heat may be concentrated at one end of the device 40 to heat the portion of the coiled hair adjacent the head.

2. A device of the class described comprising an open ended inner tube of substantially uniform bore, an outwardly extending 45 rear plate affixed thereto whereby said device may be supported in substantially horizontal position, an insulating ring surrounding said tube and disposed adjacent said plate, an outer tube having a rear end telescoping 50 said ring abutting said plate and having a relatively blunt frusto-conical front end engaging said inner tube, heating means disposed between said tubes and within the frusto-conical end and an electric conductor 55 leading through said rear plate to said heating means.

3. A hair waving device adapted to be placed on a person's head comprising a member including two telescoped metallic tubes 60 fastened together at one end to form a closed space adapted to contain a coil of the person's hair, an electric heating coil carried by said member between the metal tubes and adjacent the closed end, an outwardly extending 65 plate affixed to said member at the op-

posite end, a handle carried by said plate, means carried by the plate for directing an electric conductor to said heating coil, said plate including a projecting lug having a holding aperture therein whereby said device may be supported in position adjacent a person's head.

4. A device of the class described, comprising an open ended tubular member of relatively high heat conductivity and adapted to 70 surround a portion of a coil of hair adjacent the person's head and permit other portions to extend beyond opposite ends thereof, a heating means surrounding said tubular member, a sheet of insulating material disposed between the heating means and said tubular member, and means for supporting 75 said device in position.

5. In a device of the class described, a heating means adapted to surround a strand 80 of hair adjacent the person's head, the end adapted to be disposed adjacent the head including a metallic heating ring, an inclosed heating device disposed on the side of the ring opposite the side adapted to be positioned adjacent the person's head, the portion 85 of said heating device adjacent the ring being of frusto-conical form with the smaller end disposed close to the ring to maintain the same in heated condition.

6. A device of relatively high heat capacity for treating the portion of a coil of a person's hair adjacent the head without affecting the remaining portion of the coil, said device comprising an inner tubular 100 member adapted to contain the said portion of hair and to permit the other portion to extend therefrom, an outer tubular member being frusto-conical with the smaller end affixed to the inner member to form a joint to fit against or near to the person's head, the portion of said member forming the joint being of relatively high heat conductivity, a heating coil disposed between said tubular members close to the joint, said coil generating more heat adjacent the joint than at points farther removed from the joint whereby relative high temperatures can be obtained at one end of the device, so that the hair can be waved as close to the head as 105 possible.

7. A device of the class described, comprising a rear wall in the form of a circular disk forming a support for the device at the rear end of the same and having an opening therethrough, a short metal tube open at both ends and having one end inserted through the opening in said wall and fastened to the wall, the inner portion of said rear wall being reduced to form an annular shoulder, an outer tube having one end inclosing said shoulder, abutting against said rear wall and spaced from said inner tube, an electric heating means disposed between 120 said tubes and in advance of said rear wall, 125

electric leads passing through said rear wall from its outer face and connected to said heating means and a handle rigidly connected to said rear wall and offset from the opening through said wall and from the bore of said inner tube, said device in advance of said rear wall being free of projections whereby the device may be inserted into a mass of hair without entangling 10 the same.

8. In a device of the class described, a heating means adapted to surround a strand of hair adjacent the person's head, the end adapted to be disposed adjacent the head including a metallic heating ring, an inclosed 15 heating device disposed on the side of the

ring opposite the side adapted to be positioned adjacent the person's head, the portion of said heating device adjacent the ring being of frusto-conical form with the smaller 20 end disposed close to the ring to maintain the same in heated condition and an insulating member disposed between the small end of the frusto-conical heating device and said ring. 25

This specification signed and witnessed this 20th day of December, A. D., 1913.
